UNITED STATES PATENT OFFICE.

MEYER SAKS, OF CARLSTADT, NEW JERSEY.

ARM SAFETY LAMP.

Application filed March 1, 1924. Serial No. 696,131.

My invention relates to safety arm lamps, that is to lamps of a type suitable to be carried upon a person's arm, for the purpose of enabling him to see and to be readily seen 5 during the night time, or when because of darkness, a light is desirable.

More particularly stated my invention contemplates a small and compact lamp mechanism adapted to be mounted upon a person's arm and used under such condition 10 as to leave the person free to use both hands; the lamp and various parts associated with it, and including a battery whereby it is energized, being united in a single unit of 15 compact form, so constructed so as to admit of easy production in large quantities, and made of simple parts easily obtained and readily standardized.

My invention further includes a lamp 20 of the general kind here contemplated, with its various parts so arranged that while the lamp is being carried upon a person's arm and in active use, the light from it is projected in three general directions—forward- 25 ly, backwardly and sidewise, the area thus illuminated being considerable.

In addition, my invention contemplates giving the lamp such construction as to enable it to be readily held in the hand, and 30 thus used as a flash lamp.

Reference is made to the accompanying drawing forming a part of this specification, and in which like reference characters 35 indicate like parts throughout the several figures.

Figure 1 is a side view of the lamp, showing it partly in elevation and partly as broken away.

Figure 2 is an elevation of the lamp, showing it from the opposite side from that contemplated from Figure 1.

Figure 3 is a section through the lamp, and is taken upon the line 3—3 of Figure 1, looking in the direction indicated by the 45 arrows.

Figure 4 is a top plan view of the lamp, a portion thereof appearing as broken away.

Figure 5 is a perspective, showing the lamp as carried upon a person's left arm.

Figure 6 is a perspective, showing the lamp as held in a person's hand and used as a flash lamp.

A hollow casing member 7 made of sheet material, preferably metal, has the shape indicated for it in the drawing, and is provided with a bottom plate 8, and with a

pair of straight flanges 9, 10, integral with it, these flanges being somewhat longer than the casing member, as may be understood from Figures 1 and 2. An end cap 11 is 60 mounted upon the flanges 9 and 10, and is spaced a little distance away from the adjacent end portion of the casing member.

The casing member 7 is provided with a neck portion 12, set slightly inward, as may 65 be understood from Figure 3, so as to form a shoulder 13.

A member 13 of translucent material such as glass, celluloid, isinglass, sheet mica or the like, and preferably having a distinctive 70 color, such as red as here indicated, is fitted against the shoulder 13 and thus against the neck portion 12, and also into engagement with the end cap 11. The member 14, as to form, constitutes practically a continua- 75 tion of the casing member 7, as may be understood from Figures 2 and 3. The lower end of the translucent member 14 according to Figure 3 abuts squarely against the shoulder 13 so that the outer surface of the 80 member 14 is in exact registry with the outer surface of the casing member 7, no perceptible seam being present at the edges thus brought together. This renders the device smooth like a flask, and leaves no undesirable corners or edges protruding due to the joinder of the members 7 and 14 together.

A plate 15 of sheet metal, carried by the casing member 7, extends like a partition across from one side of the casing member 90 to the other, so as to constitute a shelf within the casing. The shelf 15 carries a lamp socket 16, and detachably mounted in this lamp socket is an incandescent bulb 17.

The end cap 11 is provided with an opening 18, bounded by a wall 19 of annular form, integral with the end cap 11 and extending inwardly therefrom—that is, downwardly according to Figure 3. This annular wall constitutes a lens mounting, and 100 carries a lens 20.

A blinder lid 21 is mounted in proximity to the opening 18, and is journaled upon the end cap 11 by means of a pin 22, as shown more particularly in Figures 2 and 3. 105

A dry battery 23, provided with a contact spring 24, is mounted within the casing member 30 which thus acts as a housing for the battery. A sliding switch button 25 of conventional form is used in connection with the battery 23, for the purpose of 110 turning the electric current on and off.

Mounted upon the battery casing and disposed upon opposite sides thereof are two eyes 26, 27. A strap 28 is connected with the eye 26 and is provided with a hook 29 for detachably engaging the eye 27. The strap 28 is used for securing the device upon a person's arm, and is preferably elastic. The strap 28 may be a wire spring or may be made of such material as is commonly used in the construction of armlets and garters.

A sliding door 30, made in a single piece of sheet metal, and concave on one of its faces and convex on the other, carries a leaf spring 31, for pressing against the battery and holding the latter firmly in position. By this arrangement the battery is unable to rattle or to become displaced. The door 30 carries a thumb piece 32, integral with it, for facilitating the removal and replacement of the door.

A lens 33 of clear glass is mounted upon the flat front face of the transparent member 13. The effect of the lens is to project a strong light directly ahead of the person carrying the lamp, thus enabling him to see to good advantage in the direction in which he is moving. This also enables the lamp to be seen plainly by persons in front of the operator.

The lamp is carried upon the arm 34 of a person, as indicated in Figure 5. While the lamp is thus carried, the blinder lid 21 preferably covers the opening 18, as indicated by full lines in Figure 4. The blinder lid prevents the light from shining directly upward into the face of the wearer, but the light can always pass out freely in three general directions, and the area thus illuminated is of considerable size. The operator wearing the lamp can see forwardly, and by looking around can see backwardly, while of course the light shines freely off to one side.

My lamp is well adapted for signalling, and may for this purpose be used in a number of different ways.

In some instances it is desirable to use the lamp as a flash lamp. For this purpose it is carried in the hand as indicated in Figure 6, the blinder lid 21 being in this instance shifted into such position as to leave uncovered the opening 18.

My invention is well adapted for use by persons in walking, or in riding bicycles or horses at night, say for instance along country roads; also, by watchmen on duty indoors or out of doors. It is well adapted for certain kinds of police and detective work. It can be used in the Army or Navy.

I do not limit myself, therefore, to any particular or special use to which the device may be employed. Neither do I limit myself to the particular mechanism here shown, nor to the precise form given to any part, nor

to any particular material to be employed in the construction or makeup of the article, except as specified in my claims, the scope of which is commensurate with my invention.

I claim—

1. The combination of a battery casing provided with a shelf extending through it and serving as a partition, said battery casing being further provided with flanges of greater length than said battery casing, an end cap connected with said flanges, a translucent member of sheet material carried by said battery casing and engaging said end cap so as to serve as a window, said translucent member of sheet material being so formed as to facilitate the passage of light through it in three directions from a particular point, an illuminating member carried by said partition and located at the point just mentioned, and a sliding door engaging said flanges and movable relatively to said battery casing for facilitating access to said battery casing and casing illuminating member.

2. A device of the character described comprising a casing member and an illuminating member carried by said casing member, a translucent member carried by said casing member and so disposed as to permit light from said illuminating member to pass out of said translucent member, an end cap carried by said casing member and partially bounding said translucent member, said end cap being provided with an opening to permit light to pass out of said casing member, and a blinder lid journaled at one of its edges upon said end cap, said blinder lid being movable in a plane parallel with the general plane of said end cap for the purpose of closing said opening, and means independent of said blinder cap for permitting light from said illuminating member to pass out of said casing member.

3. A device of the character described comprising a casing member and an illuminating member located within said casing member, a window for permitting light from said illuminating member to pass out of said casing member, a translucent member carried by said casing member and so disposed as to permit light from said illuminating member to pass out of said translucent member, an end cap carried by said casing member and partially bounding said translucent member, said end cap being provided with an opening to permit light to pass out of said illuminating member, and a blinder lid mounted upon said end cap and movable relatively to said opening for the purpose of closing said opening.

Signed at New York city, in the county of New York and State of New York, this 29th day of February, 1924.

MEYER SAKS.
